(57) **CLAIM**

The ornamental design for a wheel segment of a segmented wheel as shown and described.

DESCRIPTION

FIG. 1 is a top front isometric view of a wheel segment of a segmented wheel of my new design;
FIG. 2 is a front view thereof;
FIG. 3 is a rear view thereof;
FIG. 4 is a side view thereof, the opposite view, top view, and bottom view being identical;
FIG. 5 is a front view thereof shown with environmental elements;
FIG. 6 is a top-front isometric view of a wheel segment of a segmented wheel of my new design;
FIG. 7 is bottom-rear isometric view thereof;
FIG. 8 is a front view thereof;
FIG. 9 is a rear view thereof;
FIG. 10 is a top view thereof;
FIG. 11 is a bottom view thereof;
FIG. 12 is a first side view thereof;
FIG. 13 is a second side view thereof;
FIG. 14 is a top-front isometric view thereof shown with environmental elements;
FIG. 15 is a top-front isometric view of wheel segments of a segmented wheel of my new design;
FIG. 16 is bottom-rear isometric view thereof;
FIG. 17 is a front view thereof;
FIG. 18 is a rear view thereof;
FIG. 19 is a top view thereof;
FIG. 20 is a bottom view thereof;
FIG. 21 is a first side view thereof; and,
